UNITED STATES PATENT OFFICE.

JOSEPH LA FOLLETTE, OF PORTLAND, OREGON, ASSIGNOR OF FORTY-NINE ONE-HUNDREDTHS TO ELMER E. McCLARAN, OF PORTLAND, OREGON.

FOLDING SQUARE.

1,209,855.

Specification of Letters Patent. Patented Dec. 26, 1916.

Application filed April 5, 1916. Serial No. 89,118.

To all whom it may concern:

Be it known that I, JOSEPH LA FOLLETTE, a citizen of the United States, residing at Portland, county of Multnomah, State of 5 Oregon, have invented certain new and useful Improvements in Folding Squares, of which the following is a specification.

My invention relates to squares in general, and particularly to that class of such devices known as carpenters' squares, and used 10 by carpenters, builders, contractors and the like.

The objects of my invention are to produce a square that may be compactly folded 15 when not in use; to produce a square that may be unfolded and transformed into a measuring rule and straight edge; to produce a square that may be used as an angle bisector and protractor; to produce a square 20 that may be set to any pitch, angle or bevel; to produce a square that when set for any angle will give at one reading the degrees of said angle and the inclination in inches per foot corresponding thereto, and vice 25 versa; and to produce a square that may be used for laying out polygons and other geometrical figures. I accomplish the above objects, and other desirable features by means of the construction shown in the 30 drawing accompanying this specification, like characters of reference indicating like parts throughout the several views, and in which:

Figure 1 is a perspective view of my invention set for a right angle, and showing another setting in dotted lines. Fig. 2 is a perspective view of my invention folded, parts being broken away to show the construction. Fig. 3 is a perspective view of 40 my invention opened to form a rule and straight edge. Fig. 4 shows, upon an enlarged scale, a section upon line 4-4 of Fig. 2. Fig. 5 shows, upon an enlarged scale, a section upon line 5-5 of Fig. 2. Fig. 6 shows one method of using my invention for bisecting angles. Fig. 7 shows one method 45 of using my invention for laying out polygons.

In general my invention consists of two 50 blades pivotally connected and a bar pivotally attached to one of said blades and adapted to be adjustably secured to the other blade so that said bar forms the base of the triangle included between said blades and said bar, in combination with means where-

by said blades may be locked in a straight line one with the other by said bar, and graduations upon said bar.

The blades are designated 8 and 9, blade 8 being that to which bar 10 is pivoted by 60 means of a tubular or thimble rivet 11, as shown in detail in Fig. 5.

For the purpose of adjustably securing bar 10 to blade 9 I provide in said bar a longitudinal slot 12 which registers and 65 contacts with a stud 13 rigidly mounted upon blade 9 and having thereon a thumb nut 14 for the purpose of clamping bar 10 in any desired position upon blade 9. Engraved upon blade 9 is a line 15 longitudinally disposed adjacent stud 13, which line produced would pass through the center of pivot 16 which joins the blades 8 and 9. Engraved upon one side 10^a of bar 10 are 70 lines which when brought into register with line 15 indicate respectively the angle included between blades 8 and 9 in degrees. Engraved upon one side 10^b of bar 10 are lines which when brought into register with line 15 indicate respectively the inclination 75 in inches per foot of blade 8 respectively to blade 9. When set for any angle or inclination the respectively corresponding inclination or angle may be easily read from those lines registering with line 15.

Used as above described and illustrated in Fig. 1, my invention performs all the functions of a square, a bevel square, a protractor and an inclinometer.

I locate pivot 11 and stud 13 so that the 90 blades 8 and 9 form the sides of an isosceles triangle of which bar 10 is the base.

By means of this construction my invention may be used as an angle bisector, as 95 illustrated in Fig. 6, wherein 17 is the angle between lines 18 and 19 which is to be bisected. To bisect said angle produce line 18 beyond the apex of angle 17 to form angle 20 complementary to angle 17; set the square to angle 20 as shown, and then 100 place the square as shown in dotted lines with the intersection of blade 8 and bar 10 coincident with the apex of angle 17, and the blade 8 alined with one side of said angle; when the bar 10 will bisect the angle, 105 as shown at 8^a and 10^a in Fig. 6.

To lay out a polygon, divide 360 degrees by the number of angles or sides in the polygon and set the square to the resulting 110 degrees upon the scale upon side

10^a of bar 10. When thus set bar 10 bisects the angle included between any two sides of the polygon.

As a modification I provide a bar 10^c as shown in Fig. 7, having therein orifices adapted to engage stud 13, each of said orifices being adapted to set the square for producing a polygon of a given number of sides, as illustrated in Fig. 7.

10 To enable my invention to be used as a rule and straight edge I provide a stud 21 secured to blade 9 intermediate pivot 16 and stud 13. When the blades 8 and 9 are swung upon pivot 16 into a straight line the slot 12 in bar 10 will engage with the stud 21 and an extension 22 upon pivot 16, as shown in Fig. 3, thereby preserving the perfect alinement of blades 8 and 9. When folded, as shown in Fig. 2, the stud 13 enters the tubular pivot 11 and stud 21 enters orifice 23 provided therefor in blade 8; the slot 12 then engages stud 21 and extension 22, and is secured by thumbnut 14 upon stud 21, thus securely holding the square folded as shown.

25 In Fig. 1 the blades are graduated in inches, and the bar in degrees and inclinations, and it is to be understood that any desirable and suitable graduations may be placed upon one or both sides of the blades 30 without departing from the spirit of my invention.

35 My invention may be made of any size, and constructed of any material deemed convenient and suitable for a device of this character, and while I have illustrated and described a form of construction and arrangement of parts found desirable in materializing my invention, I wish to include in this application for Letters Patent all mechanical equivalents and substitutes that 40 may fairly be considered to come within the scope and purview of my invention as defined by the appended claims.

Having disclosed my invention so that 45 others skilled in the art may be enabled to construct and use same, what I claim as new and desire to secure by Letters Patent is:

50 1. In a folding square, a duality of scale bearing blades pivotally connected; a bar pivotally connected to one of said blades and adapted to be slidably connected to the opposite blade; means to secure said bar upon said opposite blade; and means whereby said bar may rigidly secure said blades in the 55 form of a straight edge or rule.

2. In a folding square, a duality of scale bearing blades; a pivot connecting said blades having thereon an extension above

the surface of one of said blades; a bar having therein a longitudinal slot, and engraved thereon a protractor scale and an inclination scale; a tubular pivot connecting said bar to one of said blades; a stud secured to one of said blades and adapted to coact with the slot in said bar and also with said tubular pivot; and a stud secured to one of said blades intermediate said first mentioned stud and said extension upon the pivot connecting said blades.

3. In a folding square, a duality of blades 70 pivotally connected; a bar pivotally connected to one of said blades; means whereby said bar is guided upon said opposite blade so that for any setting of said blades an isosceles triangle is formed by said blades 75 and said bar; means to clamp said bar in said guiding means; means whereby said bar may secure said blades in a straight line one extended from the other upon opposite sides of their pivotal point; and means whereby 80 said bar may secure said blades in a position folded one upon the other about their pivotal point.

4. A mechanic's folding square comprising 85 a duality of scale bearing blades pivotally connected; a stud upon one of said blades; a pivot upon the other of said blades, said stud and said pivot being equi-distant from the pivotal connection of said blades; a slotted bar mounted upon said pivot and 90 coacting with said stud to slide substantially transversely upon the stud bearing blade; said bar having engraved thereon a protractor scale and an inclination scale, the latter being adapted to register with said stud bearing blade.

5. A mechanic's folding square comprising 95 a duality of scale bearing blades pivotally connected; a slotted bar pivotally connected to one of said blades; a stud upon one of said blades adapted to coact with said slotted bar, and to cause said blades and said bar always 100 to preserve the geometrical relation of the three sides of an isosceles triangle; said slotted bar having thereon a protractor scale 105 and an inclination scale, the latter adapted to register with the stud bearing blade.

In witness whereof I claim the foregoing as my own I hereunto affix my signature in the presence of two subscribing witnesses, at 110 Portland, county of Multnomah, State of Oregon, this 29th day of March, 1916.

JOSEPH LA FOLLETTE.
